UNITED STATES PATENT OFFICE

EDGAR COCKS, OF SOUTH PASADENA, CALIFORNIA, ASSIGNOR TO LOS ANGELES WALL BED COMPANY, OF LOS ANGELES, CALIFORNIA, A CORPORATION OF CALIFORNIA

FOLDING BED

Application filed May 22, 1929. Serial No. 365,042.

This invention relates to folding beds, and, while applicable primarily to folding beds of the type that is fixedly attached to a wall or floor, or is fixedly mounted on a door to be carried thereby in and out of a closet, it may also be constructed with a suitable base to serve as a portable type—commonly known as a roller bed—designed to be moved into a closet for storage and out into a room for use. Necessarily beds of the latter type must be passed through a comparatively narrow doorway and to admit of this the bed frame is pivotally mounted upon a comparatively narrow portable base, to extend vertically above the base, when not in use, and to swing to a horizontal position for use.

As the bed frame is pivotally mounted on the base adjacent one of its ends, it greatly overhangs the base when lowered to horizontal position for use, and when being lowered the frame, due to its weight and that of the bedding, is unbalanced on the base, which unbalance increases as the frame nears its horizontal position. In order to check this unbalanced weight, and to lessen the physical effort required to raise and lower the frame, a series of springs are provided which connect an overhanging rear end of the frame with the base, the tensile strength of which is proportional to the unbalanced weight. As these springs merely connect two pivotal members, and as they must of necessity exert a strong contractual force, and also as the contractual force exerted increases as the frame nears its horizontal position, there is, at the same time, an increasing tendency of the base being swung relative to the frame and be thrown over on top of it. This tendency is greatest when the frame is in its horizontal position for use.

To overcome the foregoing difficulty, beds of this type have been heretofore provided with heavily weighted bases, and particularly with larger cast iron or lead weights secured to the rear side of the base, to counteract the spring force which tends to tip the base. But such means have been found to be very unsatisfactory, for the reason that they not only increase the cost of manufacture, but also greatly increase the weight of the entire

structure. The latter is objectionable for two reasons; first, increased shipping weight, and, secondly, increased weight on carpets and floors, which tends to destroy them.

In the accomplishment of the above mentioned objects, and to overcome the attendant difficulties, I have provided means whereby the objectionable weights may be eliminated from the base, lighter springs provided, which have less tendency to tip the base relative to the frame when moving to its horizontal position, and vice versa, and which does not add to but lessens the cost of manufacture.

My improvement comprises means whereby there is a frictional contact between the base and the frame, which tends to check movement, due to the unbalanced weight of the frame, in moving from vertical to horizontal position. This frictional engagement is effected by the springs and the arrangement is such that the frictional force is increased in proportion to the increased force exerted by the springs, as the frame moves toward its horizontal position—being greatest when in such horizontal position—and correspondingly lessened as the frame is returned to its vertical position.

My improvement may be embodied in various types of door and wall bed structures, with equally satisfactory results, where its use is to aid in checking the unbalanced weight of the bed frame and in minimizing physical effort in raising and lowering the frame.

The invention will be fully understood from the following description, taken in conjunction with the accompanying drawings, in which

Fig. 1 is a broken side elevational view showing the bed frame in folded closed position on the base;

Fig. 2 is a broken front elevational view showing the bed frame in folded closed position on the base;

Fig. 3 is a broken side elevational view showing the bed frame in an intermediate, or partly open, position on the base;

Fig. 4 is a broken front elevational view,

the position of the bed frame being the same as that in Fig. 3;

Fig. 5 is a perspective view of the base and head end of the bed; and

5 Fig. 6 is a fragmentary perspective view of a slightly modified form of standard mounting.

In the drawings—

The numeral 10 designates the base, which 10 comprises the cross members 11 and the side members 12 secured between the members 11 at their opposite ends to form a rectangular open frame. The cross member 11 forming the front marginal edge of the base serves as 15 a supporting means for the head 13, which may be of any convenient type of construction which will afford a pleasing appearance. The base is provided at its four corners with casters 14 which permit the entire 20 base frame, and head secured thereto, to be rolled through a door into a closet or other housing compartment. If a roller bed is not desired, the casters may be omitted and the bed may be fixedly mounted on the wall by 25 means of a bracket 15 provided with cleats 16 for engaging the head of the bed.

The bed or mattress supporting frame 17 consists of a pair of side bars 18 and cross bars 19 (one shown) which together form a 30 frame for the mattress springs 20. The bars forming the mattress frame, and also the bars forming the base frame, are of the regular angle bar type construction which affords a rigid and satisfactory type of mounting for 35 the bed parts. The members forming the head end 13 may be of light tubular construction, if desired.

As shown in Figs. 1-4, the bed frame 17 is 40 adapted to pivotally swing on the base 10, from a horizontal position, for use, into a vertical or closed position, for storage. The pivotal mounting means for the frame comprises: a pair of standards 20a secured at the opposite sides of the base to the side members 45 12 and rising vertically therefrom, a pair of brace bars 21 secured at one end to cross member 11, intermediate the ends thereof, and at their opposite ends to the standards 20a, and a pair of bearing plates 23 secured 50 to the opposite sides of the mattress frame and pivotally connected at 24 to the upper ends of standards 20a. The connection between brace bars 21 and standards 20a is shown as consisting of a bracket 22, one end 55 of which is bolted to the standard 20a and the other end of which is bolted to the rod 21.

The bearing plates 23 form an integral part of a pair of angle bars 25, secured on the 60 opposite sides of the bed frame to the side bars 18 of said frame, and depend from the inner edges of angle bars 25; the inside surfaces of the plates overlapping and resting in bearing contact with the outside faces of 65 the upper ends of the standards 20a, which

are pivotally secured to the respective bearing plates.

While this arrangement affords the best and most convenient construction, it is not necessary to a practical application of my improvement that the bed frame be pivotally mounted upon the standards 20a, or the members which effect the frictional engagement with the bed frame, as the frame may be pivotally supported upon additional standards 70 and the members 20a merely mounted adjacent thereto and in position to frictionally engage a movable surface on the frame. Plate 23 is also preferable, but this may also be dispensed with if desired. 80

The bearing plates 23 may be perforated as at 26 to afford pivotal support for a pair of mattress frame supporting legs 27, as shown in Fig. 1. The legs 27 are adapted to take the weight off the pivot pins 24 when the frame 17 is in horizontal position and fold 85 into a substantially vertical position when the frame is swung vertically on the base, the brackets 28 serving to hold the legs against the base when the bed is in its folded 90 position. Similar folding legs (not shown) are also provided for the foot end of the frame 17.

The frame 17 is provided with a cross-bar 95 29 extending parallel to the cross members 19 and positioned slightly rearward of the point of pivot of the frame on the standards 20a. Two or more contractual spiral springs 30 are interposed between the cross-bar 29 and the cross member 11 of the base 10, the 100 springs being secured to these members in the ordinary way by passing the hooked ends of the springs through perforations in the flanges of the angle bars. This series of 105 springs affords a retarding action against the unbalanced weight of the bed frame in turning from its vertical to its horizontal position, the springs being under a maximum tension when the frame is in its horizontal position. On the other hand, when the frame is raised to vertical position the 110 springs 30 tend to lighten the weight and minimize the required physical effort to effect this movement.

The cross-member 11 of the base frame 10 115 is formed of such weight and material as to be slightly yielding, or inherently yielding, so that as the tension of the springs 30 increases, due to movements of the frame 17 from vertical to horizontal position, it will 120 be bent or flexed vertically. It will be obvious that, as the member 11 is flexed vertically, there will be a lateral thrust exerted against the standards 20a, through the bars 21, at the point at which these rods are connected thereto, with a consequent lateral outward movement of their upper ends. This 125 outward flexing of the standards 20a, as shown in Fig. 4, tends to produce an increasing frictional or bearing contact between the 130

portions of the standards 20a which overlap the adjacent portions of the bearing plates 23 resting in contact therewith. As the frame 17 continues to approach the horizontal position, springs 30 are further distended and the tendency is to increase the vertical bending or flexing of cross member 11. This in turn produces an increased flexing or laterally outward movement of the upper ends of the standards 20a, resulting in an increased frictional contact between bearing plates 23 and the upper end of the standards. Downward movement of the frame 17 is, in this manner, effectively retarded, and it is not necessary to make the springs 30 of as rigid or heavy construction, as would be necessary were the retarding effect accomplished entirely by the springs 30. Accordingly, there is little tendency for the head end of the bed 20 to tip or fold over onto the frame 17 when the bed is in the horizontal position or when moving to such position. In the operation of moving the frame to vertical position the frictional contact between bearing plates 23 and standards 20a is gradually reduced as cross member 11 returns to its normal straight position. By combining the frictional control means with the proper weight of spring type connection, in this manner, it is thus possible to effectively eliminate any tendency for the head of the bed to fold over unexpectedly and injure the occupant or operator. The operation of raising and lowering the frame is accomplished with slight effort; the springs and friction control means being apportioned to counterbalance the bed frame at any point intermediate its limiting positions.

While I have shown the standards 20a mounted on the base members 12 and connected to the yielding transverse member 11 by means of the brace bars 21, this construction may be as shown in Fig. 6. There the standard 20b is shown to be of rigid or unyielding construction and fixedly mounted upon a transversely extending, vertically yieldable, bar 11a, to which the springs 30 are connected. Vertical movement or bending of the bar 11a will necessarily effect laterally outward movement of the upper end of the standard 20b, without necessity of using the brace rods 21. Bar 11a may either extend across the base, as in the case of bar 11, or it may be short, as shown in Fig. 6, mounted at one end upon a frame member 12 and having its inner end resting upon a brace bar 12a and made vertically yieldable to a certain extent by means of a spring 31, surrounding a bolt 32 passing through bars 11a and 12a, and bearing against the top surface of bar 11a to normally, yieldingly hold the latter in its lowernost position.

The foregoing detailed description has been given for clearness of understanding only, and no unnecessary limitations should

be understood therefrom, but the appended claims should be construed as broadly as permissible in view of the prior art.

What I regard as new and desire to secure by Letters Patent is:

1. A folding bed, comprising in combination: a base; standards embodied in the base; a frame pivotally mounted on the standards to swing in a vertical arc from a vertical to a horizontal position, and vice versa, said frame presenting surfaces in frictional engagement with said standards; and yielding means connecting the base and the frame and adapted to progressively increase the frictional engagement between the standards and said surfaces by pressing the standards against said surfaces as the frame moves downward. 70

2. A folding bed, comprising in combination: a base; standards embodied in the base; a frame pivotally mounted on the standards to swing in a vertical arc from a vertical to a horizontal position, and vice versa, said frame presenting surfaces in frictional engagement with said standards; and yielding means connecting the base and the frame and adapted both to directly resist the downward movement of the frame and by moving the standards to progressively increase the frictional engagement between the standards and said surfaces as the frame moves downward. 85

3. A folding bed, comprising in combination: a base; standards embodied in the base; a frame pivotally mounted on the standards to swing in a vertical arc from a vertical to a horizontal position, and vice versa, a minor portion of the frame extending to one side of the pivot axis, said standards being adapted to frictionally engage the frame; and yielding means connecting the base and said minor portion of the frame and associated with the standards, said yielding means being adapted to oppose the downward movement of the frame both by direct action on said minor portion of the frame and by moving said standards into progressively greater frictional engagement with the frame as the frame moves downward. 95

4. A folding bed comprising, in combination: a base; a member incorporated in the base having a limited yielding movement; a supporting member on the base operatively connected with the yielding member; a bed frame pivotally mounted on the supporting member to swing through an arc from a vertical to a horizontal position and vice versa; and means acting on the yielding member whereby frictional engagement between the supporting member and the bed frame is effected. 115

5. A folding bed comprising, in combination: a base; a member incorporated in the base having a limited yielding movement; a supporting member on the base operatively

- connected with the yielding member; a bed frame pivotally mounted on the supporting member to swing through an arc from a vertical to a horizontal position and vice versa; and means acting on the yielding member whereby frictional engagement between the pivot member and the bed frame is effected, said means being adapted to progressively increase the frictional engagement as the frame approaches its horizontal position.
6. A folding bed comprising, in combination: a base; a member incorporated in the base having a limited yielding movement; a supporting member on the base operatively connected with the yielding member; a bed frame pivotally mounted on the supporting member to swing through an arc from a vertical to a horizontal position and vice versa; and means acting on the yielding member whereby frictional engagement between the supporting member and the bed frame is effected, said means being adapted to progressively increase the frictional engagement as the frame approaches its horizontal position and to proportionately decrease the frictional engagement as the frame nears its vertical position.
7. A folding bed comprising, in combination: a base; a member incorporated in the base having a limited yielding movement; a supporting member on the base operatively connected with the yielding member; a bed frame pivotally mounted on the supporting member to swing through an arc from a vertical to a horizontal position and vice versa; and means acting on the yielding member whereby frictional engagement between the supporting member and the bed frame is effected, said means being adapted to progressively increase the frictional engagement as the frame approaches its horizontal position and to proportionately decrease the frictional engagement as the frame nears its vertical position and to maintain the said frictional engagement while the frame is in its horizontal position.
8. A folding bed comprising in combination: a base; a member incorporated in the base having a limited yielding movement; a supporting member on the base operatively connected with the yielding member; a bed frame pivotally mounted on the supporting member to swing through an arc from a vertical to a horizontal position and vice versa; and spring means in connection with the frame, acting on the yielding member, whereby frictional engagement between the supporting member and the bed frame is effected.
9. A folding bed comprising, in combination: a base; a member incorporated in the base having a limited yielding movement; a supporting member on the base operatively connected with the yielding member; a bed frame pivotally mounted on the supporting member to swing through an arc from a vertical to a horizontal position and vice versa; and spring means in connection with the frame, acting on the yielding member, whereby frictional engagement between the supporting member and the bed frame is effected, said spring means also connecting the yielding member and the frame to offer direct resistance to the movement of the frame as the frame approaches its horizontal position.
10. A folding bed comprising, in combination: a base; a member incorporated in the base having a limited yielding movement; a supporting member on the base operatively connected with the yielding member; a bed frame pivotally mounted on the supporting member to swing through an arc from a vertical to a horizontal position and vice versa; and spring means in connection with the frame, acting on the yielding member, whereby frictional engagement between the supporting member and the bed frame is effected, said means being adapted to progressively increase the frictional engagement as the frame approaches its horizontal position.
11. A folding bed comprising, in combination: a base; a member incorporated in the base having a limited yielding movement; a supporting member on the base operatively connected with the yielding member; a bed frame pivotally mounted on the supporting member to swing through an arc from a vertical to a horizontal position and vice versa; and spring means in connection with the frame, acting on the yielding member, whereby frictional engagement between the supporting member and the bed frame is effected, said means being adapted to progressively increase the frictional engagement as the frame approaches its horizontal position and to proportionately decrease the frictional engagement as the frame nears its vertical position.
12. A folding bed comprising, in combination: a base; a member incorporated in the base having a limited yielding movement; a supporting member on the base operatively connected with the yielding member; a bed frame pivotally mounted on the supporting member to swing through an arc from a vertical to a horizontal position and vice versa; and spring means in connection with the frame, acting on the yielding member, whereby frictional engagement between the supporting member and the bed frame is effected, said spring means also connecting the yielding member and the frame to offer direct resistance to the movement of the frame as the frame approaches its horizontal position.
13. A folding bed comprising, in combination: a base; a member incorporated in the base having a limited yielding movement; a

- supporting member on the base operatively connected with the yielding member; a bed frame pivotally mounted on the supporting member to swing through an arc from a vertical to a horizontal position and vice versa; and spring means in connection with the frame, acting on the yielding member, whereby frictional engagement between the supporting member and the bed frame is effected, 5 said spring means also connecting the yielding member and the frame, whereby the spring means is progressively, increasingly tensioned as the frame approaches its horizontal position.
- 10 14. A folding bed comprising, in combination: a base; a member incorporated in said base having a limited yielding movement; a frame pivotally mounted on the base to swing through a vertical arc from a vertical to a horizontal position, and vice versa; a braking means to retard the relative pivotal action of the frame, said braking means being actuated by said yielding member on the base; and means operatively connecting the 20 frame and said yielding member, whereby the weight of the frame is partially counterbalanced and the braking means is simultaneously actuated.
- 15 15. A folding bed comprising, in combination: a base; a member incorporated in said base having a limited yielding movement; a frame pivotally mounted on the base to swing through a vertical arc from a vertical to a horizontal position, and vice versa; a braking 30 means to retard the relative pivotal action of the frame, said braking means being actuated by said yielding member on the base; and a spring means connecting the frame and said yielding member, whereby the weight 35 of the frame is partially counterbalanced and the braking means is simultaneously actuated.
- 40 16. A folding bed, comprising, in combination: a base; a bed frame pivotally mounted on the base to swing through a vertical arc from a vertical to a horizontal position, and vice versa; means operable to retard pivotal movement of the frame, said means comprising, a member mounted on the base having limited yielding movement; a relatively fixed 45 member adapted to frictionally engage a surface movable with the frame, said relatively fixed member having connection with said yielding member, whereby movement of the yielding member will increase or decrease frictional engagement between said relatively fixed member and the relatively movable surface; and spring means connecting the bed frame and said yielding member, whereby the yielding member will be flexed on downward 50 movement of the frame to increase said frictional engagement.
- 55 17. A folding bed, comprising, in combination: a base; a bed frame pivotally mounted on the base to have an overhanging end, and 60 to swing through a vertical arc from a ver-
- tical position to a horizontal position, and vice versa; means operable to retard pivotal movement of the frame, said means comprising, a member mounted on the base having limited yielding movement; a relatively fixed member directly connected with said yielding member and having a portion frictionally engageable with a surface movable with the frame, whereby movement of the yielding member will move said relatively fixed member and increase or decrease frictional engagement between said relatively fixed member and the surface movable with the frame; and spring means connecting the overhanging end of the bed frame and said yielding member, whereby the yielding member will be progressively flexed on downward movement of the frame, to increase said frictional engagement, and correspondingly relaxed on upward movement of the bed frame, to decrease said frictional engagement.
- 70 75 80 85 90 95 100 105 110 115 120 125 130
- In witness that I claim the foregoing I have hereunto subscribed my name this 18th day of May 1929.
